SHEET FEED MECHANISM IN SHEET
HANDLING MACHINES

Oscar Kleinschmit, Leipzig-Plagwitz, Germany,
assignor to Gebruder Brehmer, Leipzig-Plagwitz, Germany, a limited partnership of Germany

Application January 26, 1932, Serial No. 589,013
In Germany February 12, 1931

22 Claims. (Cl. 270—53)

The present invention relates to sheet-handling machines and is more particularly concerned with the means for feeding folded sheets or book-sections to stitching machines.

5 Formerly it was customary in sheet or pamphlet stitching machines to place by hand the folded sheets straddle fashion over the sheet carrier by which they were thereafter conveyed to the stitching mechanism. 10 Methods for effecting this manual operation by mechanical means have been visualized. The proposals hitherto made, all culminated in the idea of arranging the requisite members so as to operate in uniform and inseparable relationship with the machine.

15 Now it may be desirable, by providing for a cut-out of the sheet feeding mechanism, so to arrange the sheet feeding mechanism as to enable also the manual feed method to be employed for certain special work, e. g. books produced in small editions, particularly valuable books, books with unusual section arrangements, pamphlets and similar productions. In order to avoid the laborious operation of dismounting the sheet feeding device when manual sheet feeding is desired the said sheet feeding device according to the present invention is so embodied in the pamphlet stitching machine as to enable its main constituents to be readily removed from the position in which they would impede the manual feed operation. This may be effected in various ways. For example, the whole apparatus may be retractable or oscillable or it or its main constituents may be arranged to be swung about a lateral vertical axis and/or about a horizontal axis.

20 According to this invention the sheet-handling machine includes a mechanical sheet feed device adapted to be readily movable to and from its operative position relative to the sheet carrier of the sheet-handling machine to permit when desired manual sheet feeding.

25 The particular method for effecting this adjustment from mechanical to manual operation or vice versa is immaterial and the invention should be seen broadly to reside in rendering this adaptation possible per se and readily convertible to the normal arrangement of the machine.

Two constructional forms of this invention will now be described by way of example and in reference to the accompanying drawings in which:

30 Fig. 1 is a side elevational view of a book-stitching machine of the swinging sheet carrier type with which is associated a readily displaceable sheet-feeding unit according to this invention, 55 while

Fig. 2 is an end elevational view of a sheet gathering and binding machine with which a readily displaceable sheet feeding unit is arranged to operate.

Referring to Fig. 1, the book-stitching machine A includes a frame 10 in which is pivotally supported a swinging saddle-shaped sheet carrier 11 which serves to position beneath the stitcher head or heads 12 of the machine the folded sheets to be stitched. The stitching machine A is preferably mounted on a suitable flat machine bed 15 and runners or rail tracks 16 are seated on the machine bed 15 to extend outwardly from the rear of the machine.

35 A sheet opening and feeding unit B comprising inversely rotating suction rolls 13 and associated sheet conveyor members 14 which form a sheet feeding device mounted upon a supporting member 17 is associated with the machine A and serves in known manner to feed mechanically to the sheet carrier 11 of the stitching machine A the sheets to be stitched.

The supporting member 17 comprises a braced quadrangular framework having its upper portion shaped to receive and position over the sheet carrier 11 the sheet opening and feeding rolls 13, while it is provided at its lowermost corners with trolley wheels 18 adapted to run on the rails 16. The bottom lateral stretchers 17a of the framework 17 are flanged to engage the rails 16 and so act as guides while a suitable clamping device 19 of any known design is secured to the machine bed and arranged to engage releasably when operated the bottom stretchers 17a of the framework 17 and so hold the unit B in the desired position.

40 As diagrammatically illustrated in this arrangement the drive for the sheet feeding unit B may be derived from a drive shaft 20 journalled in the supporting member 17 and driven from the main drive 21 of the stitching machine through a suitable train of gears 22.

In operation, the sheet feed unit is positioned closely adjacent the sheet carrier 11 and stitcher heads 12 of the stitching machine as shown in full lines in Fig. 1 and closed, folded sheets or signatures fed by the conveyor belts 14 are opened by the sheet opening rolls 13 and deposited straddlewise upon the sheet-carrier 11.

45 When it is desired to feed the stitching machine by hand instead of mechanically as above described, the framework 17 is released from the clamping device 19 and the sheet feeding unit B pushed or drawn upon the rails 16 away from the stitching machine A to the inoperative position

105 110

shown in chain dotted lines in Fig. 1. The clamping device is then operated to engage and hold the unit B in the desired position and manual sheet feeding operations are then carried out on

5 the stitching machine.

In the alternative arrangement shown in Fig. 2, the sheet gathering machine includes a frame 30 which serves to support a travelling conveyor 31 of the saddle shaped type adapted to receive and

10 gather sheets or book signatures fed thereto.

The sheet feeding unit, in this embodiment of the invention, includes an auxiliary framework 32 roughly triangular in shape, arranged with the apex thereof journalled upon a horizontal

15 shaft 33 mounted transversely of the machine frame 30 in the lower portion thereof.

The auxiliary framework 32 when in the operative sheet-feeding position has one upper projecting portion thereof extending over the travelling

20 sheet-conveyor 31 and this projecting portion of the frame carries a sheet feeding device 34 comprising inversely rotating suction rolls 35 and as-
sociated sheet conveyor belts 36.

The rearward portion of the machine frame 30
25 is provided with a pivotally mounted sleeve 37 and aligned therewith on the framework 32 is pivotally mounted a threaded sleeve or nut 38.

A threaded rod 39 is passed through the sleeve 37 and engages the threaded extremity thereof
30 with the threaded sleeve 38 while the further ex-
tremity of the rod 39 passing through the sleeve
37 is provided with a hand-wheel 40.

In operation, the sheet feeding unit is positioned as shown in full lines in Fig. 2, and when
35 so arranged serves in known manner to open and feed folded sheets straddlewise upon the travelling conveyor 31.

When it is desired to convert the machine to
40 manual sheet feed, the handwheel 40 is turned to
revolve the rod 39 which thus causes the nut 38
to traverse along the rod 39 and so draws the
auxiliary frame 32 and sheet feeding device 34
away from the conveyor 31. The frame 32 pivots
45 about the shaft 33 and moves to the inoperative
position shown in chain dotted lines in Fig. 2.
The mechanical sheet feeding device 34 is thus
removed from its position over the travelling con-
veyor 31 and the latter is left clear to receive the
book sections, folded sheets or the like manually
50 fed thereto. It is obvious that a sheet feeding
unit could readily be devised to operate upon a
vertical axis so as to swing laterally to and from
the sheet carrier of a sheet-handling machine.

The above described constructional embodi-
55 ments have been specifically described merely by
way of example and it is not desired or intended
to limit to these constructions the invention, the
ambit of which is clearly defined in the accom-
panying claims.

60 I claim:

1. Sheet handling apparatus which includes a
saddle-like sheet carrier, an automatic sheet
feeding device therefor, and means for readily
65 moving said device to and from its operative posi-
tion relative to the sheet carrier.

2. Sheet handling apparatus which includes a
saddle-like sheet carrier, an automatic sheet feed-
ing device, means for readily moving said de-
70 vice to and from its operative position relative
to the sheet carrier to permit when desired man-
ual sheet feeding, and means for retaining in the
selected position the said sheet feeding device.

3. An automatic sheet feed unit for feeding
folded sheets to a saddle-like sheet carrier com-
75 prising a movable supporting frame, a sheet feed

device mounted in said frame, and means for
positioning said sheet feed device in an operative
position relative to a sheet carrier of an as-
sociated sheet handling machine.

4. An automatic sheet feed unit comprising a
80 movable supporting frame, a suction roller sheet
feed device mounted in said frame, and means
for readily moving said sheet feed device to and
from its operative position relative to the sheet
carrier of an associated sheet handling machine. 85

5. An automatic sheet feed unit comprising a
supporting frame provided with bearing members
adapted to move upon runners, a suction roller
sheet feed device mounted upon said frame, and
means for retaining said frame in the desired po-
90 sition upon said runners.

6. A sheet handling machine including a ma-
chine frame, a pivotal saddle-like sheet carrier,
an auxiliary frame pivotally mounted in said ma-
chine frame, a sheet feeding device mounted in
95 said auxiliary frame, and means for moving
said auxiliary frame and sheet feeding device to
and from the operative position relative to the
said sheet carrier.

7. A sheet handling machine including a main
frame, a saddle-like sheet carrier, an auxiliary
frame supported upon a horizontal pivot in said
main frame, a sheet feeding device mounted on
100 said auxiliary frame, and means for positioning
said auxiliary frame and sheet feed device as
desired relatively to said sheet carrier.

8. A sheet handling machine including a main
frame, a sheet carrying device pivotally mounted
in said main frame, an auxiliary frame mounted
upon a horizontal pivot in said main frame, a
110 sheet feeding device mounted in said auxiliary
frame and adapted to be positioned relatively to
said sheet carrier, a pivoted threaded nut secured
to said auxiliary frame, a bearing sleeve secured
to said main frame, a threaded rod passing
115 through said sleeve to engage said nut, and
means for rotating said rod to move the said
auxiliary frame and sheet feed device to and
from the operative position relative to the said
sheet carrier. 120

9. Sheet handling apparatus comprising in
combination a book-binding machine provided
with a saddle-like sheet carrier, runners extend-
ing from said machine, an auxiliary frame, pro-
125 vided with bearing members adapted to move
upon said runners, a sheet feeding device mounted
in said frame, and means for releasably securing
said frame in a desired position relative to said
sheet carrier.

10. Sheet handling apparatus comprising in
130 combination a book-binding machine including
a saddle-like sheet carrier and machine drive,
runners extending from said machine, an auxiliary
frame provided with bearing members
adapted to move upon said runners, a sheet feed-
135 ing device, mounted in said frame, and adapted
to place folded sheets or book sections upon said
sheet carrier, means for retaining said auxiliary
frame and sheet feeding device in the desired
position relative to the said sheet carrier, and
means for actuating said sheet feeding device
from the machine drive of the book-binding
machine. 140

11. In combination a book-stitching machine,
an independent automatic sheet feeding unit,
145 and means for placing said unit into operative
association with said book-stitching machine.

12. In combination a sheet handling machine
provided with a movable saddle-like sheet carrier,
a sheet feeding unit, and means for moving said
150

- unit from the rear of the machine to an operative position above said sheet carrier and vice versa. 13. In a book-binding apparatus having a saddle-like sheet carrier, a feeding unit associated with the book-binding apparatus and adapted to feed sheets to said saddle-like carrier, and means for adjusting the position of said unit relative to the saddle-like sheet carrier to provide for automatic or manual feeding of sheets to said carrier. 14. In a book-binding apparatus having a sheet carrier for conveying sheets to a stitching mechanism, a sheet feeding unit associated with said apparatus and adapted to feed sheets to said carrier, and means for adjusting the position of the unit relative to said carrier to provide for automatic or manual feeding of sheets to said carrier. 15. In a book-binding apparatus having a sheet carrier for conveying sheets to a stitching mechanism, a sheet feeding unit associated with said apparatus and adapted to feed folded sheets or book sections to said carrier, means on said unit for opening folded sheets fed to the carrier, and means for adjustably positioning the unit relative to said carrier to provide for automatic or manual feeding of folded sheets to the carrier. 16. In a book-binding apparatus having a sheet carrier for conveying sheets to a stitching mechanism, a sheet feeding unit associated with said apparatus and adapted to feed folded sheets or book sections to said carrier, means on said unit for opening folded sheets fed to the carrier, said unit comprising a frame pivoted to said apparatus about a horizontal axis, and means for adjusting the position of said unit about said axis. 17. In a book-binding apparatus having a sheet carrier for conveying sheets to a stitching mechanism, a sheet feeding unit associated with said apparatus and adapted to feed folded sheets or book sections to said carrier, means on said unit for opening folded sheets fed to the carrier, and means for locking the unit in adjusted positions on the runway. 18. Sheet handling apparatus which includes a sheet carrier, an automatic sheet feeding device therefor, means on said device for opening folded sheets fed thereby, and means for readily moving said device to and from its operative position relative to the sheet carrier. 19. Sheet handling apparatus which includes a sheet carrier, an automatic sheet feeding device, means on said device for opening folded sheets fed thereby, means for readily moving said device to and from its operative position relative to the sheet carrier to permit when desired manual sheet feeding, and means for retaining in the selected position the said sheet feeding device. 20. An automatic sheet feed unit comprising a movable supporting frame, a sheet feed device mounted in said frame, means on said unit for opening folded sheets fed thereby, and means for positioning said sheet feed device in an operative position relative to a sheet carrier of an associated sheet handling machine. 21. An automatic sheet feed unit comprising a movable supporting frame, a sheet feed device mounted in said frame, means on said unit for opening folded sheets fed thereby, and means for readily moving said sheet feed device to and from its operative position relative to the sheet carrier of an associated sheet handling machine. 22. An automatic sheet feed unit comprising a supporting frame provided with bearing members adapted to move upon runners, a sheet feed device mounted upon said frame, means on said unit for opening folded sheets fed thereby, and means for retaining said frame in the desired position upon said runners.
